UNITED STATES PATENT OFFICE.

HERBERT L. CARPENTER, OF BROOKLYN, NEW YORK.

CONTAINER.

1,414,861.

Specification of Letters Patent. Patented May 2, 1922.

Application filed April 8, 1921. Serial No. 459,616.

To all whom it may concern:

Be it known that I, HERBERT L. CARPENTER, a citizen of the United States, and a resident of the city of New York, borough 5 of Brooklyn, in the county of Kings and State of New York, have invented a new and Improved Container, of which the following is a full, clear, and exact description.

This invention relates to a container, and 10 has for an object the provision of a simple, compact and rugged container which can be very easily assembled and disassembled and which in strength exceeds the strength of any one of the individual elements of which 15 it is composed when they are used separately.

Another object is to provide a simple, efficient package or container which is proof against leakage of the contents from the 20 container, and is also proof against the leakage of moisture into the container.

A further object is the provision of a container so assembled that it retains its shape and assembled characteristics even under 25 heavy stresses and, therefore, is very efficient for the transportation of materials.

A still further object is the provision of a container when desired the parts of which may be readily disassembled and collapsed 30 into a form permitting efficient, ready and economical shipment, whereby less space is occupied in the storage and shipment of the parts when disassembled.

Another object resides in the provision of 35 means whereby the rim portion may be very easily applied to the body portion and yet very firmly bind the parts together when in their ultimate position.

A further object resides in the provision 40 of means whereby the parts of the container bind the body portion together at the top and bottom edges under outward pressure from the tapered head and inward pressure from the locking rim, and which when 45 locked and bound together strengthen the body portion and form a compact unit of great strength.

A still further object resides in the provision 50 of means whereby the contents of the container are more effectively sealed against leakage and make the container practically moisture- and airproof.

A further object resides in the provision 55 of a construction for connecting the head, the rim and the body portion of the contain-

er whereby the use of a comparatively thin but strong body portion is permitted.

Another object resides in the particular construction and arrangement of parts which are hereinafter described and claimed and 60 shown in the accompanying drawings.

The invention is illustrated in the drawings, of which—

Figure 1 is a perspective view of the container;

Figure 2 is a vertical diametrical section taken through the container;

Figure 3 is a partial vertical section showing in an enlarged detail manner the method of assembling the body portion, the seal, the 70 plug or head portion and the rim portion;

Figure 4 is a side elevation of a modified form of rim showing the rim bent;

Figure 5 is a perspective view of the same rim when in position;

Figure 6 is a horizontal section taken on the line 6—6 of Fig. 5;

Figure 7 is a detail partial vertical section illustrating a modified method of assembling the parts;

Figure 8 is a perspective view of a container with a split rim applied, the container being rectangular in form; and

Figure 9 shows a rectangular body portion in its collapsed condition.

Figure 10 is a sectional perspective view of the seal for a rectangular container.

Figure 11 is a similar view of a seal for a circular container.

The preferred form of my invention, as 90 shown in the drawings, comprises a body portion 1 which is preferably made in the form of a hollow body portion open at each end or in the form of a hollow body portion open only at one end. Each end of this container is adapted to be closed by a head 2 which is preferably in the form of a wooden plug of any desired shape. The sides of this head 2 are so formed and related to the dimensions of the opening at each end of the 100 body portion 1 that the head 2 has to be forced under a certain amount of pressure into the end of the body portion and cause it to assume its proper position.

At the upper and tapered portions 3 of the head 2 there is provided an integral, outwardly extending flange portion 4. Of course, this flange portion need not necessarily be integral but is preferably so. This flange portion 4 is adapted to bear against the top of 110

the adjacent edge of the body portion 1 and form therefor a tight seal, so as to prevent the admission of moisture into the body portion, and particularly against the upper edges of the body portion. In Fig. 1 is shown a metallic strip 6' which extends from the bottom rim to the top rim 6 and which is engaged at each end by the nails 7 which at this point pass through not only the rim but the strip, the body portion, and enter the head portion 2. This construction may be used as desired, especially for rectangular containers.

As shown in Fig. 3, a sheet of material 8, such as paraffin paper, is placed over the top of the body portion prior to the attachment thereto of the head 2. This sheet of paper, or other fabric, is preferably cut to a diameter larger than the diameter of the opening in the body portion, so that when the head 2 is pressed into position it forces the paper into the end of the body portion under somewhat of a tension, in a manner similar to the tightening of a banjo head. The ends or edges of the paper extend up between the side edges of the head and the body portion; then when the rim 4 is put in position the ends of the paper are bent down between the outside upper edges of the body portion and the inner edge of the rim. In this manner a very effective seal against moisture and air is provided. This fabric also acts to prevent leakage of the contents in the event that, for one reason or another, the contents would otherwise leak out of the container.

This seal not only provides an effective seal of the container, but when made of relatively heavy material or fabric it tends to fill any space between the head and the body portion, and between the rim and the body portion, when the container is locked, thereby adding to the mechanical strength and tightness of the complete closure. The seal may be formed into shape in the process of closing the container, or it may be formed separately and placed in position when closing the container.

This body portion may be made of fibrous material, such as paper, or of any other suitable material rolled together in a plurality of laminations under pressure, and possibly with adhesive between the laminations, somewhat in the manner as shown and described in my copending application No. 459,615 filed April 8, 1921, entitled "Container". If the body portion, therefore, is formed of laminations, moisture admitted to the upper edges thereof will tend to soften these edges and weaken the strength of the container. The above-mentioned flange portion 4 effectively seals these upper edges and prevents this softening action. By reason of the taper of the plug or head 2 which engages the adjacent edge of the body por-

tion throughout its length, the body portion is made exceedingly strong and rugged, with the edges of the body portion held under pressure from the inside and outside. The flange portion not only seals the edge 70 of the body portion in the manner above described but also prevents the head from being driven too far into the body portion.

In order to fasten the head in place, I have provided also a rim, which is preferably 75 of some metal such as sheet steel, and has a right angle cross section, one of the flange portions 5 of which is adapted to lap over the top of the head 2, and the other flange portion 6 of which is adapted to lap over 80 and lie along the upper lateral face of the body portion 1. This rim may be made tight fitting so that it is driven on over the body portion and head, and at a plurality of intervals throughout its lateral surface nails 85 such as 7 may be driven through the rim and the body portion 1, into the head 2, in order to hold these three elements together.

This combination of the rim, body portion, and head portion, whereby when the nails 90 are driven in they engage all three of the above mentioned elements, results in a construction having very great mechanical strength and also keeps the fastening means at right angles to the face of the rim, whereby the use of a strong but thin body portion is permitted. The body portion would not otherwise securely support the nail or fastening means.

In order to apply the rim to the body portion, either in a square or circular container, without the need for the application of much pressure, and to prevent injury of the seal and body portion, and to obtain a tight fitting rim which may be fitted over the large 105 end of a tapered body portion if desired, I have provided a form of rim shown in Fig. 4 in which at one point the rim is split. One end 9 of this rim, which I designate by the numeral 10, overlaps the other end 11. These two overlapping end portions are their upper edges pivoted together by a pin 110 or other suitable means such as 12. Holes such as 13 and 13' are provided in these overlapping portions and are adapted under 115 certain conditions to register with each other. When a part of the rim portion 10 is bent into the position shown in Fig. 4, it will be readily perceived that the rim can be applied to the head of the container 1 120 very easily. When so applied the open portion of the rim is then bent down into the position shown in Fig. 5, in line with the main portion of the rim, whereupon the holes 13 and 13' are brought into alignment. Any 125 suitable device, such as a nail, may then be driven through the holes 13 and 13' and into the head portion 2 in a manner to that similarly described. In Fig. 6 I show the pivot pin 12, the ends 9 and 11 and a nail 14. 130

In Fig. 7 I show a head 2, a body portion 1 and a rim 4 the lower edge of which is flared out as at 15. This flare is provided to permit the fingers to more firmly grip the rim, 5 thereby facilitating its removal from the container.

In Fig. 8 I illustrate a rectangular form of container provided with a similarly-shaped rim, which is split. The action of 10 this rim is similar in every respect to the action of the split curved rim above described. In rectangular containers it may be preferable, under certain conditions, to provide an angle plate such as 16 at the corners of the container to extend between the top and bottom rim portions and reinforce 15 the container. The upper and lower ends of this angle plate may be provided with suitable apertures through which nails may be 20 driven to bind the rim, the angle plate, the body portion and the head together as a unit. This angle plate will, therefore, in addition tend to hold the upper and lower rim portions together. In Fig. 7 it may be preferable 25 to use, instead of ordinary nails, a staple 17 of the form shown, which is one integral member having nail-like end portions which are suitably embedded in the top and the sides of the head.

30 In Fig. 9 I illustrate the body portion 18 of the rectangular container in its collapsed position. This body portion may be formed by hand or by machinery, of any suitable material, either wood, fiber or paper. If 35 made of paper, it may be formed of one single sheet of material lapped on itself in the form of a plurality of laminations, which may be joined together by adhesive, if desired.

40 Figs. 10 and 11 show in sectional perspective views the particular shape and curvature of the seal portions for rectangular and curved or circular containers, illustrating the manner in which these seals are formed 45 of a continuous sheet of material extending beneath the head portion, up between the sides of the head portion and the body portion, outwardly between the flange of the head portion and the upper edges of the 50 body portion, and then downwardly along the outer edges of the body portion.

It is apparent that many modifications may be made in the structure without departing from the spirit of the invention.

55 What I claim is:

1. A container comprising a hollow body portion, a head portion for an end of said body portion, said head portion being inserted into the end of the body portion, a flange 60 portion extending outwardly from the upper end of said head portion and adapted to engage and seal the edge of the body portion, a flanged rim engaging the top of the head and the side of the body portion, and means 65 engaging with the rim, body, and head

portion to fasten the rim, the body and the head portion together.

2. A container comprising a hollow body portion, a head portion for an end of said body portion, said head portion being inserted 70 into the body portion, a flange portion extending outwardly from the upper end of said head portion and adapted to engage and seal the edge of the body portion, a flanged rim engaging the top of the head 75 and the side of the body portion, and a plurality of nails disposed through the rim, the body portion, and into the head to fasten these elements together.

3. A rim for containers, which comprises 80 a band of material having overlapping end portions, said end portions being pivoted together at one point adjacent the upper edges thereof, this pivotal engagement permitting a bending of one part of the rim 85 with respect to the other, simulating a split rim.

4. A rim for containers, which comprises a band of material having overlapping end portions, said end portions being pivoted 90 together at one point adjacent the upper edges thereof, this pivotal engagement permitting a bending of one part of the rim with respect to the other, simulating a split rim, each of said overlapping end portions 95 having an aperture therein adapted when the rim is in its ultimate operative position to be aligned with each other, and means adapted to be inserted through the aligned apertures to engage with the object to which 100 the rim is attached.

5. A container comprising a hollow body portion, a head portion adapted to be inserted into the end of the body portion, a flange on the head portion extending outwardly from the upper end of the head portion and adapted to engage and seal the upper edges of the body portion, and a rim having flanges lying adjacent the top edges of the head portion and the upper edges of the body portion, said rim having overlapping end portions pivoted together to permit bending of one part of the rim with respect to the other.

6. A rim for a container, which comprises a split band of material embracing the end of the container, the free ends of said band being pivoted to permit distortion of one portion of the rim from the plane normally occupied by the rim when applied to the container.

7. A rim for container which comprises a band of material adapted to embrace the end of container, said band having overlapping end portions, said end portions being pivoted together, this pivotal engagement permitting the movement of one part of the rim with respect to the other part, whereby the circumference of one edge of the rim is increased when so distorted.

8. A rim for containers which comprises 130

5 a band of material having overlapping end portions, said end portions being pivoted together at one or more points adjacent the upper edges thereof, this pivotal engagement permitting a bending of one part of 70 the rim with respect to the other part.

10 9. A container comprising a hollow body portion, a head portion to be inserted into an end of said body portion, an outwardly extending flange on said head portion to engage with the upper edges of the body portion, the sides of the head portion immediately beneath the flange being straight, the sides of the head portion below the 15 straight portion being tapered, and the lower edges of the head portion being rounded, a flanged rim engaging the top of the head and the side of the body portion and means engaging the rim, body and head 20 portions to fasten them together.

25 10. A container comprising a hollow body portion, a head portion to be inserted in the end of said body portion, and a split rim having free ends pivoted together to permit distortion of a part of the rim out of the normal plane of the rim to increase 30 the circumference of one edge of the rim, whereby the rim can be readily applied to the container.

35 11. A rim for containers, which comprises a band of material having overlapping edges pivoted together at one point, this pivotal engagement permitting an increased circumference of one edge of the rim when bending one part of the rim with respect to the other.

40 12. A rim for containers, which comprises a split band of material having overlapping end portions pivoted together at one point, this pivotal engagement permitting a bending of one part of the rim with respect to the other whereby the rim can be readily applied to and removed from a container, the end portions also having apertures 45 therein which are adapted to be aligned with each other to receive a fastening means when one portion of the rim is disposed in the normal position with respect to the other portion.

50 13. A seal for a container having a hollow body portion and a head to be inserted in the end of the body portion to close the same, said seal comprising a continuous sheet of material extending across beneath the lower 55 face of the head portion, between the edges of the head portion and the body portion, then over the edges of the body portion, and down the outside of the body portion.

60 14. A seal for containers having a hollow body portion and a head portion to be inserted in the end of the body portion to close the same and having an outwardly extending flange to rest on the upper edge of the body portion, said seal comprising a continuous sheet of material extending across 65

beneath the lower face of the head portion, then between the edges of the head portion and the body portion, then outwardly between the upper edges of the body portion and the lower edges of the flange, and then 70 downwardly along the outer surface of the body portion.

75 15. A seal for containers having a hollow body portion and a head portion to be inserted in the end of the body portion to close the same and having an outwardly extending flange to rest on the upper edge of the body portion, said seal comprising a continuous sheet of material extending across beneath the lower face of the head 80 portion, then between the edges of the head portion and the body portion, then outwardly between the upper edges of the body portion and the lower edges of the flange, then 85 downwardly along the outer surface of the body portion, and a rim embracing the outer end surfaces of the container, said seal extending between the rim and the body portion to form a tight seal between the rim, the body portion and the head portion 90 along the above-mentioned surfaces of contact.

95 16. A seal for containers having hollow body portions and a head portion to be inserted in the end thereof, and a rim co-operating with the head portion and the ends of the body portion, said seal comprising a sheet of material extending across beneath the lower face of the head portion, thence between the edges of the head portion and the body portion, thence over the edges of the body portion and down the outer surface of the body portion between it and the rim, said sheet of fabric forming not only an effective seal for the contents of the container but also insuring a tight fit of the head portion and the rim of the container. 100

105 17. A container construction which comprises a collapsible body portion, a head portion to be inserted in the end of the body portion, an outwardly extending flange on the head portion, said flange resting on the edges of the body portion, a rim to embrace the end of the body portion and engage with the head portion, and means engaging the 110 rim, the body portion and the head portion to fasten them together.

115 18. A container comprising a hollow body portion and a head adapted to close the end of the body portion, said head having a portion to be readily inserted within the body portion of the container and an outwardly extending flange thereon, and a sheet of sealing material disposed across the lower face of the head portion, upwardly between 120 the edges of the head portion and the body portion, then outwardly between the upper edges of the body portion and the flange portion, and then downwardly over the outer surface of the body portion. 125

19. A container comprising a hollow body portion and a head adapted to close the end of the body portion, said head having a portion to be readily inserted within the body portion of the container and an outwardly extending flange thereon, a sheet of sealing material disposed across the lower face of the head portion, upwardly between the edges of the head portion and the body portion, then outwardly between the upper edges of the body portion and the flange portion, then downwardly over the outer surface of the body portion, and a rim to embrace the outer surface of the body portion and the sheet of sealing material.
20. A container construction comprising a collapsible hollow body portion, a head to be inserted in each end of the body portion to close the same, said head having a flange to bear on the edges of the body portion, rims engaging the ends of the body portion and the flanges of the head portion, and means engaging the rims, the body portion and the head portion to fasten the same together.
21. A rim of material of relatively substantial width adapted to embrace the end
- of a container, said rim having meeting end portions, and means for connecting said end portions whereby distortion of said rim about said connecting means produces an enlarged circumference of one edge of the rim.
22. A rim of material of relatively substantial width to adapt it to embrace the end of a container, said rim having meeting end portions, and means for connecting said end portions whereby distortion of said rim about said connecting means increases the area bounded by the lower peripheral edge of the rim.
23. A seal for a container having a hollow body portion, a head portion to be placed over the end of the body portion, and a rim, said seal comprising a sheet of material extending across within the container beneath the lower face of the head portion, thence upwardly along the inner walls of the container, then across the edge of the container, and then downwardly along the outer surface of the container, the rim and head portion adapted to engage the seal to hold it in place.

HERBERT L. CARPENTER.
